BOOK SUPPORT

Vance T. Littlejohn, Greensboro, N. C.

Application April 13, 1942, Serial No. 438,822

9 Claims. (Cl. 45—57)

My invention relates to certain new and useful improvements in means for supporting a book on a table, desk, or other like body, in an open position, and so as to be easily readable.

Primarily, the present invention has for its object to provide certain new and useful improvements in and to the book support which constitutes the subject matter of my application for patent filed January 19, 1942, Ser. No. 427,381, in virtue of which the scope of usefulness of a support of that character may be increased.

The present invention not only enables an ordinary book (bound at a side) to be supported as disclosed in my prior application aforesaid, but enables one to support a spirally bound stenographer's notebook in open position for convenient readability.

Again, the present invention has for its object to provide means for supporting books whose covers along the backbone are glued down, such as some typewriting manuals.

Another object is to provide a book support having means for holding down the pages of the book being supported.

Other objects will in part be obvious and in part be pointed out hereinafter.

To the attainment of the aforesaid objects and ends the invention still further resides in the novel details of construction, combination and arrangement of parts, all of which will be first fully described in the following detailed description, and then be particularly pointed out in the appended claims, reference being had to the accompanying drawings, in which:

Fig. 1 is a front elevation showing my improved book support, supporting a spirally bound notebook.

Fig. 2 is a side elevation of the parts shown in Fig. 1, looking from right to left in that figure.

Fig. 3 is a detail central vertical section through the head of the support and showing how the legs may be rotated to a position where they may be enclosed between the leaves of a book to which the support may be applied, when not in use.

Fig. 4 is a detail plan view of the head end of the support.

Fig. 5 is a detail cross section on the line 5—5 of Fig. 3.

Fig. 6 is a side view, showing how the support may be attached to a book having an unglued cover back along the backbone, between which cover back and the leaf rib or binder-back the shank or blade of the support is placed.

Fig. 7 is a view similar to Fig. 4, showing a modified form of leaf holder.

Fig. 8 is a perspective view of a book holder for books having the cover glued down along the backbone.

Fig. 9 shows how the book is clamped to the shank of the support, parts of the book being broken away.

Fig. 10 is a view of the parts shown in Fig. 8, looking at the under side (in Fig. 8) of the shank, the legs being swung about 120° from their working position, shown in Fig. 8, and partly broken away.

Fig. 11 is a detail central vertical section of the head end of the support with a leg in working position in dotted lines and in the non-working position in full lines.

In the accompanying drawings, in which like numerals of reference indicate like parts in all the figures, 1 represents the shank, which in the embodiment of Fig. 1 is round in cross section, and 2 indicates the head which is bifurcated. On the opposed faces of the furcations grooves 3 are provided which make an angle of 60° with the shank 1.

Between the furcations the head 2 has a stop-incline 5 against which the legs 8 of the device, when not in use, lie (see dotted lines, Fig. 3, and dot and dash lines, Fig. 1).

Projecting from the head 2 and parallel to the shank 1 is a clip 6. When the spirals 16 of the notebook 15 are placed on shank 1 some of them will be forced between the shank 1 and the clip 6, thereby holding the device in place (Fig. 1).

The legs 8 are pivoted on a pin 7 between the furcations and when brought together the combined thickness of the legs is slightly less than the space between the furcations of the head so that the legs can be swung about the pivot pin 7 from the full line position in Fig. 1 to the dot and dash line position in that figure. The openings 9 in the legs, for pin 7, are slightly elongated or larger in diameter than that of the pin so as to permit the legs to be spread apart into grooves 45 3 (Fig. 5).

The legs 8 have feet 10 which, when the device is in use (Figs. 1 and 2), rest on the desk, table, etc., along their lengths and hold the shank 1 parallel to the desk, table, etc. on which the device is set.

When using the support on ordinary books 18, which are bound on a side and have a space between the back 17 and the leaf rib, the parts assume the position shown in Fig. 6, the feet resting on their toe ends.

The ends of the legs 8 which are located in the head 1 are beveled as at 11 so that those ends will lie in contact when the legs are spread apart in the grooves 3 (see Figs. 4 and 5).

The head 2 is provided with slideable leaf holders 12 secured in place (in the embodiment of Figs. 1 to 6 inclusive) by clips 14 and having stops or finger-pieces 13. In the modified form (Fig. 7) the leaf holders 12^a are slotted bars secured in place by screws 14^a, there being one holder 12^a on each furcation 2^a of the head. In Fig. 7 those parts which correspond to similar parts in Fig. 6 bear the same reference number plus the index letter *a*.

Referring now to the modification shown in Figs. 8 to 11, inclusive, it will be seen that I have provided a flat shank 19 carrying the bifurcated head 20, grooved at 21, and carrying a pivot pin 22. The shank 19 is recessed or cut out, as at 24, to receive clamp blocks 25 held in place by thumb screws 26 or the like (Fig. 8). Opposite the blocks 25 the shank 19 is formed with a clamp rib 23.

In this form of the invention, as in the others, the legs 28 have beveled ends 27 and feet 29, the latter being parallel to and beneath the shank 19 when in use and spread apart so as to lie in the 60° grooves 21.

In use the glued back 30 of the book is placed on the shank 19 between the stops 25 and clamp-rib 23 and the screws 26 are tightened firmly to grip the book (Fig. 9). The covers 31—32, of course, rest on the table, desk, etc. on which the book is supported, with the leaves 33 exposed to view.

By making the angle of the grooves 3 and 21 60°, instead of 90° as shown in my application aforesaid, the prop is made more substantial, a better balance is ensured, the support takes up less space on the table or desk, and it is possible to use practically all types and sizes of typewriting manuals and spirally bound stenographer's notebooks as well as ordinary books in connection with the invention.

Other advantages of my invention will readily appear to those skilled in the art.

From the foregoing description, taken in connection with the accompanying drawings, it is thought that the construction, operation and advantages of the invention will be clear to those skilled in the art.

What I claim is:

1. A book support comprising a shank, a bifurcated head at one end of the shank, a pair of legs one end of each of which is pivoted between the furcations of the head, the opposed faces of the head having leg-receiving grooves located at angles of approximately 60° to the shank, said legs being capable of being spread apart to lie in said grooves or brought flatwise together for pivotal movement, and means to mount said shank on the back of the book to be supported.

2. A book support comprising a shank, a bifurcated head at one end of the shank, a pair of legs one end of each of which is pivoted between the furcations of the head, the opposed faces of the head having leg-receiving grooves located at angles of approximately 60° to the shank, said legs being capable of being spread apart to lie in said grooves or brought flatwise together for pivotal movement, means to mount said shank on the back of the book to be supported, and feet on said legs, said feet lying parallel to said shank when said legs are in said grooves.

3. A book support comprising a shank, a bifur-

cated head at one end of the shank, a pair of legs one end of each of which is pivoted between the furcations of the head, the opposed faces of the head having leg-receiving grooves located at angles of approximately 60° to the shank, said legs being capable of being spread apart to lie in said grooves or brought flatwise together for pivotal movement, means to mount said shank on the back of the book to be supported, said means to mount said shank on a book comprising a clamp rib on the shank, at least one clamp block, and a screw to hold said block to the shank and cooperate with said rib to clamp the back of the book between them.

4. A book support comprising a shank, a bifurcated head at one end of the shank, a pair of legs one end of each of which is pivoted between the furcations of the head, the opposed faces of the head having leg-receiving grooves located at angles of approximately 60° to the shank, said legs being capable of being spread apart to lie in said grooves or brought flatwise together for pivotal movement, means to mount said shank on the back of the book to be supported, and leaf holders mounted on the furcations of the head.

5. A book support comprising a shank, a bifurcated head at one end of the shank, a pair of legs one end of each of which is pivoted between the furcations of the head, the opposed faces of the head having leg-receiving grooves located at angles of approximately 60° to the shank, said legs being capable of being spread apart to lie in said grooves or brought flatwise together for pivotal movement, means to mount said shank on the back of the book to be supported, feet on said legs, said feet lying parallel to said shank when said legs are in said grooves, and leaf holders mounted on the furcations of the head.

6. A book support comprising a shank, a bifurcated head at one end of the shank, a pair of legs one end of each of which is pivoted between the furcations of the head, the opposed faces of the head having leg-receiving grooves located at angles of approximately 60° to the shank, said legs being capable of being spread apart to lie in said grooves or brought flatwise together for pivotal movement, means to mount said shank on the back of the book to be supported, said means to mount said shank on a book comprising a clamp rib on the shank, at least one clamp block, and a screw to hold said block to the shank and cooperate with said rib to clamp the back of the book between them, and leaf holders mounted on the furcations of the head.

7. A book support comprising a shank, a bifurcated head at one end of the shank, a pair of legs one end of each of which is pivoted between the furcations of the head, the opposed faces of the head having leg-receiving grooves located at angles of approximately 60° to the shank, said legs being capable of being spread apart to lie in said grooves or brought flatwise together for pivotal movement, means to mount said shank on the back of the book to be supported, and leaf holders mounted on the furcations of the head, said holders each comprising a slideable bar mounted for movement parallel to said shank to project over the leaves of the book to which the shank may be applied.

8. A book support comprising, a shank insertable lengthwise between the back and the leaf binding of a book, a bifurcated head on said shank, a pair of legs pivotally mounted in the slot between the furcations of said head, and transverse grooves in the head, said legs being con-

structed so that they may be spread apart at their free ends to lie in part in said transverse grooves when the support is in use to support an open book.

9. A book support comprising, a shank insertable lengthwise between the back and the leaf binding of a book, a clip on said shank to overlie the top edge of the book back, a bifurcated head

5 on said shank, a pair of legs pivotally mounted in the slot between the furcations of said head, and transverse grooves in the head, said legs being constructed so that they may be spread apart at their free ends to lie in part in said transverse grooves when the support is in use to support an open book.

VANCE T. LITTLEJOHN.
